CLAIM

The ornamental design for a toilet assist device, as shown and described.

DESCRIPTION

FIG. 1 is a front perspective view of a toilet assist device showing the new design;

FIG. 2 is a front elevation view thereof;

FIG. 3 is a right elevation view thereof;

FIG. 4 is a back elevation view thereof;

FIG. 5 is a left elevation view thereof;

FIG. 6 is a top plan view thereof;

FIG. 7 is a bottom plan view thereof;

FIG. 8 is another front perspective view thereof showing the toilet assist device in the context of a toilet;

FIG. 9 is another front perspective view of a toilet assist device showing the new design;

FIG. 10 is another front elevation view thereof;

FIG. 11 is another right elevation view thereof;

FIG. 12 is another back elevation view thereof;

FIG. 13 is another left elevation view thereof;

FIG. 14 is another top plan view thereof;

FIG. 15 is another bottom plan view thereof; and,

FIG. 16 is another front perspective view thereof showing the toilet assist device in the context of a toilet.

The broken lines in the drawings are for the purpose of illustrating portions of the article that form no part of the claimed design.
